UNITED STATES PATENT OFFICE.

JOHN A. BLAKE, OF WATERTOWN, NEW YORK.

VISE.

SPECIFICATION forming part of Letters Patent No. 258,980, dated June 6, 1882.

Application filed April 3, 1882. (No model.)

To all whom it may concern:

Be it known that I, JOHN A. BLAKE, of the city of Watertown, county of Jefferson, and State of New York, have invented a new and useful Improvement in Vises, which improvement is fully set forth in the following specification.

This invention relates to vises or instruments for clamping and holding firmly an article to be operated upon, and which consist mainly of two clamping-jaws and means for moving one of them toward and away from the other. As commonly constructed the adjustment of the movable jaw is effected solely by the operation of a screw, by which also the desired pressure is brought upon the article held between the jaws; but in order to change the position of the jaw to suit articles of different sizes a great many turns of the screw are often necessary, whereby much time is lost. Many devices have, however, been heretofore made for effecting a rapid adjustment of the movable jaw, whereby the latter can be moved back and forth independent of the screw, which need be resorted to only to produce the desired pressure on the article held between the clamping-jaws. To this class of vises the present invention more particularly relates. It also relates in part to vises which are swiveled or pivoted to a bed-plate secured to the workman's bench or table, so as to be capable of turning thereon, and are provided with means for clamping the vise on its bed-plate or support when in use. In such vises as generally constructed the means for connecting the vise to its support are of such a nature that the clamping of the vise so as to hold it stationary when in use and the releasing it when it is desired to turn it to some other position cannot be effected without inconvenience and loss of time.

In the present invention the movable jaw is carried by a slide adapted to move freely back and forth in an opening made longitudinally through the main body of the vise under the fixed jaw. The slide is hollowed out from below and contains a ratchet-toothed or rack bar adapted normally to engage with a series of teeth or projections fixed on the bottom of the opening in which the slide moves. The end of the rack-bar or toothed bar is screw-threaded

and enters a threaded nut held in the end of the hollow slide and capable of turning by the usual cross-bar or handle passing through the head of the nut. A spring interposed between the rack-bar and top of the slide keeps the former in engagement with the teeth or projections below it, so that by turning the nut by means of its handle the nut, by reason of its engagement with the threaded end of the rack-bar, is moved back or forward, and carries with it the slide and movable jaw. The movement, however, that can thus be imparted to the jaw is slow, and is moreover limited by the length of the threaded nut, so that when the jaw is to be moved a greater distance than can be effected by the screw, or when it is desired to make the adjustment rapidly, it is only necessary to press downward on the head of the nut, which lifts the rack-bar out of engagement with the teeth below it, leaving the slide free to be moved the desired distance.

The bottom plate of the vise, which is circular in form, rests upon a hollow annular casting adapted to be secured to the workman's bench or table, and on said bottom plate is formed an annular shoulder or projection, which fits in said hollow casting and holds the vise in place, while permitting it to be turned thereon. By means of a clamping spider-plate, a threaded bolt, nut, and handle, or wrench for turning the same, the vise may be clamped firmly upon its support during use by turning the handle in a proper direction, and by turning it in the opposite direction the clamping-plate is loosened and the vise is free to turn upon its support.

The accompanying drawings, which form a part of this specification, represent a vise constructed in accordance with the invention.

Figure 1 is a longitudinal vertical section; Fig. 2, a vertical cross-section on line 2 2 of Fig. 1; Fig. 3, a view, partly in elevation and partly in section, of the slide and rack-bar; and Figs. 4 and 5, perspective views of the bottom of the vise and of the base or support, respectively.

A is the fixed and B the movable jaw. The latter is carried by the slide C, which is supported and moves in an opening formed under the jaw A. The slide C is hollowed out from

below, so as to contain the toothed bar or rack-bar D, which is normally kept in engagement with the teeth or projections E, formed in the bottom of the opening in which the slide moves, 15 by the leaf-spring d. The outer end of rack-bar D is screw-threaded, and engages with an internal thread formed in nut F, through the outer end or head of which passes the ordinary cross-bar or handle, G. The nut F is held in one end 20 of slide C, so as to be capable of turning freely. It is held in its bearing by the shoulder f bearing against the outer end of the slide, and by the spring f², surrounding the nut and held between the end of the slide and the collar f' on 25 the nut F. When the parts are in the position shown in Fig. 1 the turning of the nut F by means of its handle G will cause the movable jaw B to approach or recede from the fixed jaw A through the engagement of the nut with 30 the threaded end of rack-bar D, the latter being firmly held by the teeth or projections E. The bar D has a slight vertical play in the slide C, so that when it is desired to draw out the slide without resorting to the operation of the 35 screw it is only necessary to press downward on the head of nut F, which will lift the inner end of the nut, and with it raise the bar D clear of the teeth E, as shown in Fig. 3, and permit the slide to be drawn out. The lifting of bar 40 D can best be effected by grasping the handle G in the position shown in Figs. 1 and 3 and pressing firmly upon it in the direction of the arrow, Fig. 1. This causes the nut F to turn on the point f as a center and raises the rack- 45 bar D against the pressure of spring d into the position shown in Fig. 3. Without removing the pressure upon the handle G the slide rack-bar and movable jaw can be drawn out the required distance. Handle G being released, the 50 bar D is returned to its former position by the spring d and drops into engagement with the tooth or teeth opposite it.

The jaw B can be moved in the opposite direction—that is, toward jaw A—by simply 45 pushing in the slide C, the incline of the teeth and the yielding of spring d permitting the bar D to ride over the teeth or projections E.

As an additional support to the slide C, a forwardly-projecting lip, a, is formed on the body 50 of the vise.

The spiral spring f² bears at one end on the collar f' on nut F and at the other against the end of the slide. This serves to steady the nut in its bearing and keep it from vibrat- 55 ing, while at the same time permitting the small movement necessary to lift the rack-bar D.

The pin c in the end of slide C, by its contact with teeth E, prevents the slide being drawn 60 out too far. When for any purpose it is desired to withdraw the slide altogether the pin c is removed.

The bottom plate, H, of the vise is circular in form, and is provided at a short distance from 65 its edge with an annular projection, h', which fits into the hollow circular casting K, which forms the bed-plate or support for the vise and

is adapted to be screwed to the workman's bench or table. The flat portion h of the bottom plate, H, rests upon the top of support K, 70 and turns thereon. The support K is formed with an inwardly-projecting annular rim or collar, k, against which rests the spider-plate L, held in place by screw-bolts l l'. The bolt l screws into the bottom plate of the vise, but 75 not tight enough to clamp the spider-plate L against the collar k of piece K, and therefore does not interfere with the turning of the vise. The bolt l' passes through spider-plate L and bottom plate, H, and a threaded 80 nut, m, engages with it, and when screwed tight clamps the rim or collar k of support K firmly between the plates L and H, thus holding the vise immovable upon its support. By loosening the nut m sufficient to release the 85 pressure of the spider-plate L the vise is released, and can be freely turned upon the support K, the spider-plate turning with it. For convenience in operating nut m, a handle or wrench, m', is provided, fitting over the nut m, 90 which has angular faces. The handle is left in place upon the nut, as shown, Fig. 2, and forms a permanent part of the instrument. A slight turn of the handle to the right will loosen the nut m, so that the vise can be re- 95 volved. By this arrangement the clamping of the vise to its bed-plate or support for use and the releasing it therefrom to adjust it to a different position are very readily and quickly effected. 100

To prevent bolt l' turning with the nut m, its shank is made square at l' and fits in a square hole in the spider-plate L. The head of bolt l' is also cut away to form a shoulder, as shown in Fig. 2, which bears against the edge of sup- 105 port or bed-plate K.

It is obvious that modifications may be made in the details of construction without departing from the spirit of the invention, and also that parts of the invention can be used separately. For example, instead of a number of fixed teeth E, a single tooth or projection could be used, though for the sake of greater strength the construction shown is deemed preferable. 110

Having now fully described my said invention and the manner of carrying the same into effect, what I claim is—

1. The combination, with the movable jaw and its slide, of a toothed bar contained in said slide and screw-threaded at one end to engage 120 with an internal thread in a nut held in the end of said slide, and a series of fixed teeth or projections for engaging said toothed bar, the latter having sufficient vertical play in said slide to enable it to be lifted out of engagement with said teeth or projections by pressing downward on the head of said nut, substantially as described.

2. In a vise, the combination of the movable jaw carried by a slide which works in an opening formed in the body of the vise below the fixed jaw, an internally-threaded nut and handle for turning the same, a toothed bar thread- 130 ed at one end and engaging with said nut, one

or more fixed teeth or projections for engaging said toothed bar, and a spring bearing upon said bar and tending to keep it in engagement with said teeth or projections, substantially as described.

5 3. The combination of the hollow slide, nut turning in the end of said slide and having a collar formed thereon, and a spiral spring encircling said nut and bearing at one end against 10 said collar and at the other against the end of said slide, substantially as and for the purpose set forth.

15 4. The combination of the hollow support provided with an internal shoulder, the bottom plate of the vise fitting in and turning on

said support, the spider-frame fitting in said support and against said shoulder, screws for attaching said frame to the bottom plate, nut engaging one of said screws, and handle for turning said nut, said screw being eccentric to 20 the axis of the vise and said handle and nut above the bottom plate, substantially as described.

In testimony whereof I have signed this specification in the presence of two subscribing 25 witnesses.

JOHN A. BLAKE.
